UNITED STATES PATENT OFFICE.

WILLIAM J. KENT, OF NEW YORK, N. Y.

DESIGN FOR A HOOF-PAD.

SPECIFICATION forming part of Design No. 33,089, dated August 14, 1900.

Application filed June 27, 1900. Serial No. 21,851. Term of patent 14 years.

To all whom it may concern:

Be it known that I, WILLIAM J. KENT, a citizen of the United States, residing in the city of New York, borough of Brooklyn, county of 5 Kings, and State of New York, have invented and produced a certain new and original Design for a Hoof-Pad, of which the following is a specification.

This design relates to hoof-pads for horses, 10 and pertains particularly to articles of this character which are known as "bar-pads."

The new design relates to the shape and surface ornamentation of the pad.

My present design is shown in the accompanying drawings, in which—

Figure 1 is an obverse or bottom face view of a bar-pad embodying the new design, and Fig. 2 is a reverse or top face view thereof.

Referring to the drawings, let A indicate 20 the obverse face and B the reverse face of a bar-pad.

C is the rear end; D, the front end. E is the thin portion, and F is the outline or edge of the pad.

25 A distinctive feature of my new design is the tapering convex protuberance G on the obverse side of the pad, which projects outwardly and downwardly and has its widest portion at the heel end of the pad, tapering 30 to a rounded small end toward the front of the pad and terminating near the middle thereof. This is a- shaped in its longitudinal section and projects downwardly from the bottom face H of the heel and then re- 35 cedes upwardly to meet the portion E at its front a. The sides b of the protuberance ex-

tend upwardly in acute curves and angles. The bottom face H of the heel is of less downward projection than is the protuberance G, and at each side of the latter the pad has upwardly-extending curved walls c, merging upwardly and forwardly until they meet the portion E. The protuberance G has a surface composed of a plurality of longitudinally-extending tapering projections d and 40 intermediate recesses e. It is bordered on its front side by a band f, corresponding in contour to the front end a of the protuberance and having outwardly-curving portions g at its extremities where it meets the walls c. 50 The remainder of the obverse face is flat and smooth.

Another distinctive feature is that the reverse or top face of the pad is a plain face and has a central concavity I, disposed opposite the protuberance G, which concavity is of approximately-triangular outline, having rear wall h, converging side walls i, and corners j.

The new design is of distinctive shape and 60 pleasing appearance.

What I claim is—

The design for a hoof-pad, substantially as herein shown and described.

In witness whereof I have hereunto signed 65 my name in the presence of two subscribing witnesses.

WILLIAM J. KENT.

Witnesses:

GEORGE H. FRASER,
THOMAS F. WALLACE.
